US00D659690S

(12) **United States Design Patent**
Huang

(10) **Patent No.:** **US D659,690 S**
(45) **Date of Patent:** **** May 15, 2012**

(54) **PORTABLE ELECTRONIC DEVICE**

(75) Inventor: **Chih-hua Huang**, New Taipei (TW)

(73) Assignees: **Askey Technology (Jiangsu) Ltd. (CN)**;
Askey Computer Corp. (TW)

(**) Term: **14 Years**

(21) Appl. No.: **29/398,758**

(22) Filed: **Aug. 4, 2011**

(30) **Foreign Application Priority Data**

Jul. 12, 2011 (TW) 100303583

(51) **LOC (9) Cl.** **14-03**

(52) **U.S. Cl.** ..... **D14/240; D14/138 G**

(58) **Field of Classification Search** D14/240,

D14/242, 357, 358, 140–140.2, 140.5, 155,
D14/137, 138 R, 138 G, 138 AD, 348, 349,
D14/351, 354, 355; 375/222; 455/557; 709/203,
709/217–250; 725/111

See application file for complete search history.

(57) **CLAIM**

The ornamental design for a portable electronic device, as
shown and described.

DESCRIPTION

FIG. 1 is a perspective view of a portable electronic device
showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 5 Drawing Sheets

FIG. 1

FIG. 2

FIG. 3

FIG. 4

FIG. 5

FIG. 6

FIG. 7
